(57) **CLAIM**

The ornamental design for a nozzle for container, as shown and described.

DESCRIPTION

FIG. 1 is a front perspective view of a nozzle for container; FIG. 2 is a front view thereof, the opposite side being a mirror image of the side shown herein;

FIG. 3 is a left side view thereof, the opposite side being a mirror image of the side shown herein;

FIG. 4 is a top view thereof; and,

FIG. 5 is a bottom view thereof.

The portion shown by broken lines is for illustrative purposes only and forms no part of the claimed design.
